Primary Examiner — Kelley Donnelly*(74) Attorney, Agent, or Firm* — Honigman Miller Schwartz and Cohn LLP; Douglas H. Siegel; Jonathan P. O'Brien(57) **CLAIM**

The ornamental design for a socket tray, as shown and described.

DESCRIPTION

FIG. 1 is a front perspective view of the socket tray;

FIG. 2 is a rear perspective view thereof;

FIG. 3 is a left-side elevation view thereof;

FIG. 4 is a right-side elevation view thereof;

FIG. 5 is a top-elevation view thereof;

FIG. 6 is a bottom-elevation view thereof;

FIG. 7 is a front plan view thereof; and,

FIG. 8 is a rear plan view thereof.

The broken lines in the figures show portions of the socket tray which form no part of the claimed design.

1 Claim, 4 Drawing Sheets(56)
